UNITED STATES PATENT OFFICE.

KARL KURT LEDIG, OF NEWARK, NEW JERSEY, ASSIGNOR OF ONE-HALF TO OTTO A. LEDIG, OF NEWARK, NEW JERSEY.

SMOKING-PIPE ATTACHMENT.

1,274,904.

Specification of Letters Patent.

Patented Aug. 6, 1918.

Application filed February 20, 1917. Serial No. 149,809.

To all whom it may concern:

Be it known that I, KARL KURT LEDIG, a citizen of the United States, and a resident of Newark, in the county of Essex and State 5 of New Jersey, have invented a certain new and useful Improvement in Smoking-Pipe Attachments, of which the following is a specification.

The present invention relates to tobacco 10 smoking pipes, and more particularly to an attachment to be applied to the same.

An object of the present invention is to provide an attachment adapted to be fitted to a pipe to retain the tobacco and the ashes 15 therein during use, and prevent burning tobacco and ashes being blown or falling out of the pipe bowl on windy days, when traveling in motor vehicles, and the like, and when stooping or jumping during work or sport; 20 thereby preventing injury by burning and by ashes to surrounding persons and objects.

The invention further aims at the provision of an attachment of this character for automatically tamping and holding in 25 packed condition the tobacco placed in the bowl, to insure the uniform and steady burning of the same, and to keep the tobacco burning after once lighted.

A still further object of the present invention 30 is to provide an attachment embodying the above characteristics, and which is so constructed and arranged as to protect the tobacco from undue moisture in rainy weather when the ordinary pipe cannot be 35 conveniently used.

The above, and various other objects and advantages of this invention will be in part described, and in part understood, from the following detailed description of the present 40 preferred embodiment, the same being illustrated in the accompanying drawings wherein:

Figure 1 is a side elevation of a pipe having the attachment of this invention applied thereto.

Fig. 2 is a top plan view of the same.

Fig. 3 is a longitudinal section taken through the pipe and the attachment applied thereto.

Fig. 4 is a top plan view of the bowl end of the pipe, showing the attachment swung to one side to admit filling of the bowl.

Referring to this drawing, 10 designates an ordinary pipe bowl provided with a stem 55 part 11 to which is fitted a mouthpiece 12.

The attachment comprises a disk 13 adapted to fit comfortably in the bowl 10 and provided with a plurality of openings or perforations 14 extending through the disk. The disk 13 is carried upon one end of an arched support which is in the form of a rod bent substantially U-shaped having one arm 15 secured to the middle portion of the disk 13 to provide a plunger rod for moving the disk longitudinally in the pipe bowl 10. 60

The intermediate portion of the arched support extends substantially radially from the central axis of the bowl 10 and is spaced from the open end of the bowl. This intermediate portion of the support forms a handle 16 adapted to be grasped in the fingers for withdrawing and positioning the disk 13 with respect to the bowl 10. 70

The opposite or outer end of the arched support is pivotally mounted in any suitable 75 manner at the side of the bowl 10. In the present instance, the pipe is so formed as to provide at one side of the bowl a casing or cylinder 17, the longitudinal axis of which is substantially parallel to that of the bowl 80 10. The outer end of the support forms a pivot stem 18 which projects into the cylinder 17, and which is provided upon its free end with an enlarged head 19 adapted to fit for sliding movement in the cylinder 17. 85 The stem 18 carries an expanding spring 20 which has one end resting against the head 19, and which has its opposite end detachably bearing against a cap 21 which is detachably secured to the outer end of the cylinder 17. The cap 21 may be threaded into the outer end of the cylinder 17 to form a support for the spring 20 and also provide a pivotal bearing for the stem 18. The stem 18 is of greater length than the plunger 15 to 90 retain the arched support in pivotal engagement with the casing or cylinder 17 when the disk 13 is drawn upwardly out of the pipe bowl 10. 95

In using this attachment the tobacco is 100 packed in the pipe bowl 10 in the usual manner after the device has been swung to one side, as shown in Fig. 4. The user now grasps the handle 16 and swings the support over the pipe bowl 10 to register the disk 13 with the bore of the bowl. When the handle 16 is now released the spring 20 urges the arched support inwardly and forces the disk 13 against the tobacco in the bowl to tamp the same and hold it in packed position. As 110

the disk 13 is provided with the openings 14, air is admitted to the tobacco to permit the same to burn. The spring 20 advances the disk or follower 13 against the tobacco as the latter is burned so as to keep the same tightly packed in the bowl and thus secure the even and continuous burning of the tobacco.

It is evident that in rainy weather the 10 bowl 10 may be inverted and the disk 13 will retain the tobacco in the bowl. When the pipe is used in the wind, is handled roughly, or is laid on one side, the tobacco will be retained in the bowl under all of 15 these conditions as the spring 20 constantly urges the disk 13 into the bowl against the tobacco and the ashes formed therein.

To gain access to the bowl, it is only necessary to draw the handle 16 upwardly against 20 the tension of the spring 20 until the disk 13 clears the upper edge of the bowl. The arched support may now be swung laterally to move the disk 13 out of register with the bowl. The handle 16 may of course be released, at which time the spring 20 draws the arched support downwardly and holds the disk against one side of the bowl.

It is evident that the attachment may be 30 made entirely separate from the pipe and adapted to be applied to pipes of different construction, and also that other modifications and changes may be made in the details of construction of the above-specifically described embodiment of this invention without departing from the spirit thereof, such 35 changes and modifications being restricted only by the scope of the following claims.

I claim:

1. The combination with a pipe having a 40 bowl, of a perforated disk adapted to fit in the open end of the bowl, an arched support pivotally mounted at one side of the bowl and extending into the open end there-

of and having connection with said disk, and a spring supported by the bowl and engaging 45 said arched support for normally urging the same inwardly to feed said disk against tobacco packed in the bowl.

2. The combination with a pipe having a bowl, a disk fitting in the open end of the 50 bowl, a cylinder mounted at one side of the bowl, an arched support having one end projecting into said bowl and the other end projecting into said cylinder, the end of said support projecting into the bowl having connection 55 with said disk to support and carry the same, a head on the other end of the support in said cylinder, a spring surrounding the support and engaging said head, and a detachable cap surrounding the support 60 against the spring for securement to the open end of said cylinder.

3. The combination with a pipe having a bowl, of a U-shaped support having one end 65 engaging in said bowl, a pivot bearing engaging about the other end of the support, a disk mounted on said first end of the support in the open end of the bowl, and a spring surrounding said other end of the support with one end connected to the extremity thereof and its opposite end engaging against said pivot bearing 70 to urge the support axially inward.

4. In a pipe, the combination of a bowl 75 provided with a cylinder at one side thereof having its axis substantially parallel with that of the bowl, a U-shaped support having an end projecting into the cylinder, a spring in the cylinder engaging the adjacent end of the support to draw the latter into the cylinder, and a perforated disk carried upon the other end of the support adapted to engage 80 in said bowl to form a follower for packing the tobacco in the bowl as the latter is consumed.

KARL KURT LEDIG.
